US00D988398S

(12) **United States Design Patent** (10) Patent No.: **US D988,398 S**
(45) Date of Patent: ** Jun. 6, 2023

(54) **INK REPLENISH CONTAINER**

(71) Applicant: **SEIKO EPSON CORPORATION**,
Tokyo (JP)

(72) Inventors: **Noriyuki Fukasawa**, Matsumoto (JP);
Taku Ishizawa, Matsumoto (JP);
Tadashi Watanabe, Matsumoto (JP);
Ryoichi Tanaka, Shiojiri (JP);
Tadahiro Mizutani, Shiojiri (JP)

(73) Assignee: **SEIKO EPSON CORPORATION**,
Tokyo (JP)

(**) Term: **15 Years**

(21) Appl. No.: **29/744,727**

(22) Filed: **Jul. 31, 2020**

Related U.S. Application Data

(60) Continuation of application No. 16/675,851, filed on Nov. 6, 2019, now Pat. No. 11,117,379, which is a division of application No. 15/617,682, filed on Jun. 8, 2017, now Pat. No. 10,471,723.

(30) **Foreign Application Priority Data**

Mar. 1, 2017 (JP) 2017-037829

Primary Examiner — Lauren D McVey

CLAIM

The ornamental design for an ink replenish container, as shown and described.

DESCRIPTION

FIG. 1 is a front view of an ink replenish container showing our new design, the rear view being a mirror image of FIG. 1; and,

FIG. 2 is a front, top and right side exploded perspective view thereof.

The broken lines illustrate portions of the ink replenish container that form no part of the claimed design.
